WATER COOLED FURNACE WALL

Application filed August 27, 1928, Serial No. 131,872. Renewed April 6, 1931.

This invention relates to a furnace wall particularly adapted for boilers, in which water tubes connected to the water spaces of the boiler or other suitable source of supply 5 of cooling fluid constitutes a portion of the furnace wall and serves to support or aid in supporting the remainder of the wall. The invention will be best understood from the description in connection with the accompanying drawing, in which Fig. 1 is a perspective view, partly broken away, showing the tubes and the supporting means; Fig. 2 is a section along the line 2—2 of Fig. 1; Figs. 3, 4 and 5 are similar views showing 15 modifications; Fig. 6 is a vertical section through a portion of a wall embodying the invention; and Fig. 7 is a section on the line 7—7 of Fig. 1.

In the illustrative embodiment, reference 20 character 10 indicates water tubes of a boiler that may be connected to the circulating system of a boiler. As indicated in Fig. 6, these tubes 10 may be connected to headers 25 and 26, from which header connections are made 25 to the circulating system of the boiler in the well-known manner, which is not necessary to describe or illustrate. The tubes 10 constitute a portion of the furnace wall and serve to support certain of the wall forming elements, as will be described below. These 30 tubes are shown in Fig. 6 as being bent near their upper ends so as to extend to the outside of the furnace wall. These tubes are also disposed with their axes in substantially the 35 same plane and when we refer herein to "the plane of the tubes" it will be understood that we mean the plane referred to above and which embraces the axes of the tubes.

Metallic or tile holding members are placed 40 between the tubes 10. Each one of these holding members comprises a horizontal flat portion or plate 11 and a vertical flat portion or plate 13 integral with the portion 11 and extending at substantially right angles to the 45 plane of the tubes. The portion 11 has a somewhat restricted or narrow neck portion between its ends, and enlarged end portions that are rounded, as shown at 12, to fit against the tubes 10. The vertical flat portion 13 is 50 disposed at right angles to the flat portion 11,

and the flat portion 13 extends beyond the edge of the flat portion 11 on one side and terminates in a bulbed edge 14. The holding members, comprising the flat portions 11 and 13 at right angles to each other, can be installed 55 between the tubes 10 by tilting the same so that the portion 11 is inclined, whereupon the plate 11 can be inserted between the tubes and then turned into a horizontal position, with its concave ends 12 resting 60 against the outside surfaces of adjacent tubes, and with the flat portion 13 in a vertical plane. A plurality of these holding members may thus be installed in superposed relation, so that the flat portions 13 rest upon and sustain 65 each other in a vertical row.

The vertical portions 13 are provided with vertical slots 15 on each side of the flat portion 11. These slots 15 are wide enough to accommodate rectangularly shaped flat 70 plates 16 disposed in the plane of the tubes and that are long enough to extend across the space between the tubes 10 and wide enough to extend from the flat portion 11 to the end of the slot 15, or wide enough, so that the 75 upper edge thereof as shown at 16', will extend from such a slot in one vertical portion 13 into a corresponding slot in the lower portion 13 of the next superposed holding member, thus closing the space between two 80 tubes 10 from the horizontal portion 11 of one holding member to the corresponding portion of the next holding member.

After the holding members have been installed between the tubes 10 with the flat 85 plates 16 in place, tile or refractory material 18 is installed on the furnace side of the wall, as shown in Fig. 2, this tile resting upon and being supported by the edges of the flat portions 11, and preferably being applied in 90 plastic form so as to be substantially continuous monolithic between tubes and in a vertical direction, as plainly shown in Fig. 7. The tubes are partially exposed, and the result is, therefore, a wall formed of alternate 95 sections of water-cooled surfaces and refractory surfaces, with the refractory surfaces held in position by the water-cooled ones, through the medium of the holding members. Insulating material 19 is installed so 100

as to form the outside of the wall or the portion of the wall from the plates 16 to the outer face of the same. This insulating material 19 is likewise supported by the horizontal portions 11 of the holding members, and is retained in place by the bulbed edges 14. This insulating material is not subjected to such intense heat as the inside of the wall, as the water tubes protect the same and absorb heat that would otherwise reach this material, such absorption being assisted by the holding members contacting with the water tubes.

We may provide two bulbed portions on the vertical portions 13 of the holding members, as shown in Fig. 3, so that two layers 19 and 20 of insulating material may be applied to form the outside of the wall, the layer 20 being made of less refractory material and, therefore, cheaper than the layer 19, thus decreasing the cost of the wall. Instead of having two bulbed portions on the members 13, we may depend upon the adhesiveness between the insulating layers 19 and 20 to retain the layer 20 in place, as illustrated in Fig. 4 of the drawing.

In the modification shown in Fig. 5, the horizontal portion 11' of each holding member between the tubes 10 is made so that the same can be inserted between the tubes without tilting, although their ends are rounded out to fit the tubes. The slots 15' in this modification are made in line with the outer edge of the portion 11', so that the flat plates 16' are almost in line with the outer edges of the tubes 10. In order to retain the holding members in place when made as just described, small pieces of steel 17 may be welded to the tubes 10 in such positions as to hold the plates 16' in contact with the tubes. In this view, we also show a modification for holding the insulating layer 20 in place, without requiring the vertical members 13' to project outwardly into the insulating layer 20. This means comprises wire gauze or thin metal 21, which may be fastened to the bulbed parts of the vertical portions 13' in any convenient manner, so that the intermediate portions will become embedded in the insulating material 20 and retain the same in place.

As illustrated in the drawing, portions of the water tubes 10 are exposed to radiant heat. It will be obvious, however, that the tile 18 may be made thicker and extend farther around the tubes 10, until the edges thereof contact with each other, thus shielding the tubes 10 from the radiant heat of the furnace if desired. When it becomes necessary to remove a tube 10 for repair, this can be done with the modification shown in Figs. 1 to 4 by first removing the tile and then cutting or breaking off the edges of the horizontal portions 11 of the holding members that lie next to the inside of the furnace, and then remov-

ing the tubes without disturbing the layers of insulating material. After removal of an old tube a new tube can be inserted in its place. The holding members still support the refractory and insulation, as this has not been materially disturbed by the foregoing operation. If preferred, the tubes may be replaced by removing the refractory and insulation, but preferably the first described method is followed when renewing the tubes. In the modification shown in Fig. 5, it is not necessary to cut or break off any portion of the holding members, as the same can be removed merely by taking off the tile and then cutting away the pieces of steel 17 which hold the vertical plates 16' in place.

Fig. 6 shows the tubes 10 holding the insulating layers 19 and 20 of the wall in place as above described, and these tubes are bent at their upper ends to pass through holes in the tile 22 and holes through the portion 23 of the wall that is supported upon I-beams 24, and enter the header 26. The holes through the portion 23 through which the tubes 10 pass are large enough to provide room for the tubes to move due to expansion and contraction. With one of the headers 25 or 26 fixed in position, and the other free to move when the tubes expand or contract, a sliding joint is provided between the tube cooled portion of the wall and another portion of the same thus providing for relative motion between the two portions.

While we have shown the invention as embodied in a specific form, it is to be understood that various changes in details may be made without departing from the scope of the invention, and we therefore do not intend to limit ourselves except by the appended claims.

We claim:

1. A furnace wall comprising parallel water tubes, and supports for insulating material between said tubes, each support comprising a horizontal and a vertical plate, one extending at right angles to the tubes and the other parallel thereto and spaced therefrom.

2. A furnace wall comprising water tubes, and supports for insulating material between said tubes, said supports comprising horizontal plates that fit between said tube and vertical members holding said plates in spaced relation to each other.

3. A furnace wall comprising vertical water tubes, supports for insulating material between said tubes, said supports comprising horizontal plates that fit between said tubes, and vertical plates that extend beyond one edge of each of said horizontal plates and are disposed between adjacent tubes and spaced therefrom.

4. A furnace wall comprising vertical water tubes, supports for insulating material between said tubes, said supports comprising

- horizontal plates that fit between said tubes, and vertical plates whose vertical edges contact with adjacent tubes.
5. A furnace wall comprising water tubes, supports for insulating material between said tubes, said supports comprising horizontal plates that fit between said tubes, vertical plates that contact with said tubes, and vertical plates at right angles to said last named 10 plates.
6. A wall supporting member comprising a horizontal plate with concave ends and a vertical plate intersecting the horizontal plate intermediate its ends.
- 15 7. A wall supporting member comprising a horizontal plate with concave ends adapted to engage wall tubes, and a vertical plate, said vertical plate having a slot therein adapted to receive a second vertical plate.
- 20 8. A wall supporting member comprising a horizontal plate with concave ends adapted to engage wall tubes, and a vertical plate, said vertical plate having a slot therein, and a second vertical plate in said slot.
- 25 9. A wall supporting member comprising a horizontal plate with concave ends adapted to engage wall tubes, and a vertical plate, said vertical plate having a bulbed portion.
- 30 10. A furnace wall comprising a plurality of vertical tubes, supporting members disposed between said tubes and comprising horizontally disposed spaced plates, and vertical plates having their edges substantially in contact with the tubes.
- 35 11. A furnace wall comprising a plurality of vertical tubes, a plurality of horizontal plates spaced from each other and disposed between said tubes, and vertical plates between said horizontal plates and having their 40 vertical edges extending parallel to the axes of said tubes.
- 45 12. A furnace wall comprising a plurality of tubes with their axes in substantially the same plane, a plurality of horizontal plates disposed between said tubes and spaced apart, a plurality of vertical plates perpendicular to the plane of the tubes and disposed between the tubes, and a plurality of vertical plates also disposed between the 50 tubes substantially parallel to the plane thereof.
- 55 13. A furnace wall comprising a plurality of tubes with their axes in substantially the same plane, a plurality of horizontal plates disposed between said tubes and spaced apart, a plurality of vertical plates perpendicular to the plane of the tubes and disposed between the tubes, and a plurality of vertical plates also disposed between the tubes substantially 60 parallel to the plane thereof, said first named vertical plates having projections thereon for the purpose set forth.
- 65 14. A furnace wall comprising a plurality of parallel tubes spaced apart, and supporting members disposed between said tubes,
- each member comprising plates disposed in three planes at right angles to each other.
15. A furnace wall comprising a plurality of parallel tubes spaced apart, and supporting members disposed between said tubes, each member comprising plates disposed in three planes at right angles to each other, one of said plates being disposed transversely to the length of the tubes and having its edges adjacent the tubes formed with concave portions adapted to engage the tubes. 70
16. A furnace wall comprising a row of tubes disposed substantially parallel to each other, a layer of refractory material and a layer of insulating material, a plate separating said layers, means carried by each plate to hold both layers in position with respect to the plate, and means engaging the tubes to hold the plate in position. 75
17. A furnace wall comprising a row of spaced substantially parallel vertically extending tubes, a closure for the space between two adjoining tubes and formed in sections, plates forming shelves on said sections extending inwardly towards the interior of the furnace and transversely of said tubes, a lining supported by said shelves, and means for holding said sections in place. 80
18. A furnace wall comprising a row of spaced substantially parallel vertically extending tubes, a closure for the space between the adjoining tubes, plates forming shelves disposed on said closure and extending inwardly towards the interior of the furnace and transversely of said tubes, a lining supported by said shelves, and means for holding said closure in place. 85
19. A furnace wall comprising a row of spaced substantially parallel vertically extending tubes, substantially continuous refractory material disposed in the spaces between said tubes and contacting therewith, metallic members disposed between adjacent tubes in the row and disposed vertically one above the other, with parts of said members between said adjacent tubes substantially contacting with each other and thus supporting each other, said members partially embracing and loosely engaging said adjacent tubes to thereby prevent movement of the members laterally of the tubes while permitting movement longitudinally thereof, and means on said members to hold said refractory material in engagement therewith. 90
20. A furnace wall comprising a row of spaced substantially parallel vertically extending tubes, substantially continuous refractory material disposed in the spaces between said tubes and contacting therewith, a part of each tube between adjacent portions of refractory material being exposed to the heat of the furnace, metallic members disposed between adjacent tubes in the row and disposed vertically one above the other, with parts of said members between said adjacent 100 tubes. 110
- 115
- 120
- 125
- 130

- tubes substantially contacting with each other and thus supporting each other, said members partially embracing and loosely engaging said adjacent tubes to thereby prevent movement of the members laterally of the tubes while permitting movement longitudinally thereof, and means on said members to hold said refractory material in engagement therewith.
- 10 21. A furnace wall comprising a row of spaced substantially parallel vertically extending tubes, metallic plates closely spaced along said tubes and forming shelves extending outwardly from said tubes into the spaces therebetween approximately in the plane of the row of tubes and so arranged as to substantially bridge said spaces, means to hold the shelves in position relative to the tubes, a substantially continuous monolithic refractory material disposed on said shelves and extending between said adjoining tubes but leaving a part of each of said tubes between portions of said material exposed to the heat of the furnace, and a substantially continuous 25 backing extending lengthwise of the tubes and contacting with said refractory material and cooperating with said shelves to hold said material in place.
22. A furnace wall comprising a row of spaced substantially parallel vertically extending tubes, metallic plates closely spaced along said tubes and forming shelves extending outwardly from said tubes into the spaces therebetween approximately in the plane of the row of tubes and so arranged as to substantially bridge said spaces, means including welding to said tubes to hold the shelves in position relative to the tubes, a substantially continuous monolithic refractory material 30 disposed on said shelves and extending between said adjoining tubes but leaving a part of each of said tubes between portions of said material exposed to the heat of the furnace, and a substantially continuous backing 35 extending lengthwise of the tubes and contacting with said refractory material and cooperating with said shelves to hold said material in place.
